UNITED STATES PATENT OFFICE.

HENRY L. FERRIS AND HOWARD J. FERRIS, OF HARVARD, ILLINOIS, ASSIGNEES TO HUNT HELM, FERRIS & COMPANY, A CORPORATION OF ILLINOIS.

DOOR HANGER AND TRACK.

No. 919,288.

Specification of Letters Patent. Patented April 20, 1909.

Original application filed March 11, 1908, Serial No. 420,470. Divided and this application filed July 18, 1908. Serial No. 444,155.

To all whom it may concern:

Be it known that we, HENRY L. FERRIS and HOWARD J. FERRIS, citizens of the United States, residing at Harvard, in the county of McHenry and State of Illinois, have invented a new and useful Improvement in Door Hangers and Tracks, of which the following is a specification.

Our invention relates to certain new and useful improvements in door-hangers and tracks, and is fully described and explained in the specification and shown in the accompanying drawing, in which:

Figure 1 is an elevation of our improved hanger; Fig. 2 is the top plan of the hanger; Fig. 3 is a transverse section in the line 3 of Fig. 1, showing the hanger in position in a track; and Fig. 4 is a section in the line 4 of Fig. 1.

Referring to the drawing, A is a hollow cylindrical track slotted at the bottom and supported by brackets, one of which is designated by *a*, in Fig. 3. The track may be of any well known form as far as our present invention is concerned, but in the preferred form it is constructed after the manner set forth, described and claimed in our application filed March 11, 1908, Serial No. 420,470. Two rollers B are provided, each generally

spherical in form, the ends being, however, flattened to provide bearings as illustrated, the rollers being of such curvature as to run easily upon the inner surface of the track A and conform generally thereto. The rollers are supported by axles C between which and the rollers are interposed anti-friction rollers *c*, the axles being supported between the ends of frame-members D. The frame-members

D are preferably made of cast metal and have their outer ends spaced apart to receive between them the rollers B and perforated to receive the axles C which in practice are riveted or up-set at their ends to hold the ends of the frame-members together. The frame-

members are medially brought together and at a point midway between the axles C to afford pivotal support for a door-supporting loop E, which extends through the bottom slot in the track and is attached to the door by any usual means, preferably by a strap F passed over a rod forming the lower portion of the door-supporting loop E.

In the preferred form of construction the door-supporting loop E is pivoted to the frame-members D below the plane of the axles C and thereby the construction is made particularly stable against lateral oscillation. This is due to the fact that the weight is thus supported from a point below the center of gravity of the rollers and thereby prevents the rollers B from oscillating in a lateral direction, and the consequent contacting of the sides of the loop E with the edges of the bottom slot in the track and the resulting friction and binding of said parts. The loop E is thus caused to travel in a straight line in the slot and free from attrition with the sides thereof. Furthermore, the fact that the door-supporting loop is pivoted to the hanger-frame-members permits the hanger-frame to oscillate with respect to the door so as to take up any inequalities or irregularities in the track surface. This makes the hanger easier to move longitudinally in the track than would be a hanger rigidly secured to the door and relieves strains which would otherwise be thrown on the connecting device between the hanger and the door which might tend to loosen and destroy the same or weaken the wood of the door.

We realize that considerable variation is possible in the details of construction of our improved device, without departing from the spirit of our invention and we do not intend, therefore, to limit ourselves to the specific form herein shown and described.

What we claim as new and desire to secure by Letters Patent, is—

1. The combination with a hollow cylindrical track slotted on its lower face, of a frame within the hollow of the track, rollers journaled at opposite ends of the frame and engaging the inner surface of the track and conforming to the curvature thereof, and a door-supporting portion pivotally secured to the remainder of the frame and extending through the slot in the track, the pivotal support of the door-supporting portion upon the remainder of the frame being located below the plane of the axes of the rollers.

2. The combination with a hollow-cylindrical track slotted on its lower face, of a frame-member comprising two members in

separated relation within the same, rollers | the door-supporting portion being located
journaled between the ends of said frame-
members, and being of a contour to conform
to the inner surface of the track, a door-sup-
porting portion pivotally secured between
said frame-members extending through the
slot in the track and adapted to be secured
to the door, the point of pivotal support of

HENRY L. FERRIS,
HOWARD J. FERRIS.

In presence of—
E. B. HUNT,
JOHN W. CHAFFEE.
